CARPET.

No. 20,303.

Patented Nov. 18, 1890.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 20,303, dated November 18, 1890.

Application filed October 20, 1890. Serial No. 368,736. Term of patent 3½ years.

To all whom it may concern:

Be it known that I, JAMES L. FOLSOM, of the city of Brooklyn, county of Kings, State of New York, have invented a new and original

5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

15 The accompanying photograph is a face view of a carpet showing my new design.

My design consists of the body A and border B. The body A consists of conventionalized stars surrounded by wavering rays and

diminishing in distinctness. The border B consists of apparently superposed approximately semicircular forms and of the conventionalized star-shaped forms with wavering rays of diminishing distinctness running into a serrated border ornamented with gem-shaped figures. 25

What I claim is—

1. A design for carpets, consisting of the body A, substantially as shown.
2. A design for carpets, consisting of the border B, substantially as shown.
3. A design for carpets, consisting of the body A and border B, substantially as shown. 30

JAS. L. FOLSOM.
